UNITED STATES PATENT OFFICE

104,628

DESIGN FOR A COMBINED LAMP AND HORN

Jeremiah D. Kennelly, Oak Park, Ill., assignor of one-half to Ethel V. Mars

Application October 21, 1936, Serial No. 65,410

Term of patent 7 years

To all whom it may concern:

Be it known that I, Jeremiah D. Kennelly, a citizen of the United States, residing at Oak Park, in the county of Cook and State of Illinois, have invented a new, original, and ornamental Design for a Combined Lamp and Horn, of which the following is a specification, reference being had to the accompanying drawing, forming a part thereof, in which:

Figure 1 is a side elevational view of a combined lamp and horn showing my new design; Fig. 2, a top plan view, and Fig. 3, a front face view in elevation.

I claim:

The ornamental design for a combined lamp and horn as shown.

JEREMIAH D. KENNELLY.
